(57) **CLAIM**

The ornamental design for a dental solution pen applicator, as shown and described.

DESCRIPTION

FIG. 1 is an isometric view of a dental solution pen applicator.

FIG. 2 is a left side view of the dental solution pen applicator in a first configuration.

FIG. 3 is a left side view of the dental solution pen applicator in a second configuration.

FIG. 4 is a right side view of the dental solution pen applicator in the first configuration.

FIG. 5 is a right side view of the dental solution pen applicator in the second configuration.

FIG. 6 is a top view of the dental solution pen applicator.

FIG. 7 is a bottom view of the dental solution pen applicator opposite the top view of FIG. 6.

FIG. 8 is an enlarged front view of the dental solution pen applicator; and,

FIG. 9 is an enlarged rear view of the dental solution pen applicator.

The broken lines showing various elements of the dental solution pen applicator are included for the purpose of illustrating non-claimed subject matter and form no part of the claimed design.
